(57) **CLAIM**

I claim the ornamental design for an alignment target apparatus, as shown and described.

DESCRIPTION

FIG. 1 is a front perspective view of the alignment target apparatus of our new design.

FIG. 2 is a top plan view of the target apparatus shown in FIG. 1; and,

FIG. 3 is an end elevational view of the target apparatus shown in FIG. 1.

The broken line showing of structure is included for the purpose of illustrating non-claimed subject matter and forms no part of the claimed design.
